UNITED STATES PATENT OFFICE.

MICHAEL H. WHALEN, OF NEW YORK, N. Y.

SPIITTOON.

1,160,553.

Specification of Letters Patent.

Patented Nov. 16, 1915.

Application filed April 14, 1915. Serial No. 21,263.

To all whom it may concern:

Be it known that I, MICHAEL H. WHALEN, a citizen of the United States, residing at New York, county and State of New York, have invented certain new and useful Improvements in Spittoons, of which the following is a full, clear, and exact specification.

This invention relates to spittoons or cuspidors, and has for its object to provide a receptacle of this kind which is sanitary and presents an appearance which is not unsightly.

A further object is to provide means for conveying or guiding the saliva to a place of concealment within the body of the receptacle.

Other objects will appear as the description proceeds.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:

Figure 1 is a central vertical section of a spittoon made substantially in accordance with the present invention. Fig. 2 is a plan view with the cover removed, and Fig. 3 is a detailed edge view of the conical member or shed.

The body 1 of the spittoon may be cylindrical in form and closed at the bottom, as at 2, the top being open. Removably fitted in the top open end is a cover 3 having a depending flange 4 to engage the inner wall of the body and properly center the cover. The middle portion of the cover is depressed forming an inverted truncated cone 5 terminating in an opening 6 arranged centrally of the receptacle.

Removably fitted in the bottom of the body 1 is an improved form of shed 7 which is generally conical in form, the cone surface 8 extending from the apex, which is arranged centrally of the receptacle and about on a level with the mouth or opening 6 of the cover, to the peripheral edge from which depends a flange 9 of a size to fit within the body 1.

At intervals around the edge portion of the conical member there are formed gables

or peaks 10 arranged radially of the cone and extending from a point 11 about midway between the apex and periphery, to the flange 9 which may be extended up to the ridges of the gables, as shown in Fig. 3. Between adjacent gables openings 12 are formed in the cone surface 8, said openings extending near to the bases or sides of the gables.

The construction described is such that saliva entering the receptacle through the opening 6 in the cover will be delivered upon the central raised portion of the conical member 7, either directly on or near the apex thereof, and flow by gravity down the inclined surface of the cone 8 so as to be out of sight through the opening 6. This flow of the saliva down the surface of the cone will continue until it is delivered through one of the openings 12 into the bottom of the casing or body 1 of the receptacle. If the saliva happens to flow in the direction of one of the gables 10 instead of directly to one of the openings 12, said gable will divert its course to one or the other of the openings which extend near to the sides of the gable, so that the saliva will ultimately reach one of the openings in any event.

Having thus described my invention, what I claim as new and desire to secure by Letters Patent of the United States is:—

1. In a spittoon, the combination with a body, of a cover having an inclined surface leading to a central opening, and a conical shed arranged within the body and having spaced openings in the peripheral portion of its conical surface, and gables arranged between said openings for the purpose specified.

2. In a spittoon, the combination with a body, of a cover having an inclined surface leading to a central opening, and a conical shed arranged within the body and having spaced openings in the peripheral portion of its conical surface, gables arranged between said openings, and a vertical flange depending from the periphery of the shed for supporting it above the bottom of the body.

3. In a spittoon, the combination with a body, of a cover having an inclined surface leading to a central opening, and a conical shed arranged within the body and having spaced openings in the peripheral portion of its conical surface, and gables arranged between said openings with their ridges extending radially of the cone.

4. In a spittoon, the combination with a body, of a cover having an inclined surface leading to a central opening, and a conical shed arranged within the body and having spaced openings in the peripheral portion of its conical surface, and gables arranged between said openings with their sides extending near to the edges of the openings.
5. In a spittoon, the combination with a body, of a cover having an inclined surface leading to a central opening, and a conical shed made of sheet material arranged within

the body with its apex below the opening in the cover, said shed having spaced openings in its peripheral edge and radially arranged gables between said latter openings and formed by bending the portions of said peripheral edge of the shed between adjacent openings into the shape of inverted V in cross section, for the purpose specified. 15

In testimony whereof I have signed my name to this specification. 20

MICHAEL H. WHALEN.
